SANITARY STORAGE CABINET

Edward Dornbush, Miami Beach, Fla., assignor to
Tropical Concrete Products, Inc., Hialeah, Fla.

Application May 11, 1949, Serial No. 92,590

2 Claims. (Cl. 312—329)

1

This invention relates to sanitary storage cabinets and has particular reference to such cabinets for the storage of garbage cans, trash cans and many other types of containers that require constant removal from and replacement within the cabinet.

An important object of the present invention resides in a cabinet formed of precast sections connected and sealed together and provided with a closure door constructed in a manner to be self-closing.

Another object of the invention resides in a cabinet having the above named characteristics, with a self-closing door provided with a bracket that is supported from the inner side thereof for the reception of storage cans or the like and adapted to swing with the door for the removal of and replacement of the said cans from within the cabinet.

A further important object of the invention resides in the novel manner of supporting the bracket upon the inside of the door, whereby the bracket is wholly supported from the axis of the door hinge pins and whereby the supported can or the like is off-balanced in a manner that causes the door to be automatically closed when released.

A further object of the invention resides in a cabinet of the above named characteristics that maintains the supported can free from contact with the walls and bottom of the cabinet, is easily swung to exposed position by the door and upon release swings by gravity to the closed and concealed position, possesses few and simple parts, is effective protection against rodents and other animals, is sanitary, cheap to manufacture, requires a minimum of effort to remove and replace the can, is ornamental in appearance and highly effective in use.

Other obvious advantages of the invention will be readily apparent during the course of the following description, reference being had to the accompanying drawings, wherein is illustrated a preferred embodiment of the device.

In the drawings:

Figure 1 is a perspective view of the cabinet in the closed position.

Figure 2 is a similar view with the closure door swung to open position.

Figure 3 is a vertical longitudinal section of the cabinet, taken on line 3—3 of Figure 1.

Figure 4 is a similar view with the door open, taken on line 4—4 of Figure 2.

Figure 5 is a horizontal section taken on line 5—5 of Figure 3.

2

Figure 6 is a perspective view of the precast sections forming the cabinet, in separated position before assembly.

Figure 7 is a slightly enlarged perspective view of the closure door and associated parts, removed from the cabinet and,

Figure 8 is an enlarged section through the hinge mounting for the door, taken on line 8—8 of Figure 5.

Like numerals are employed to designate like parts throughout the several figures of the drawing.

Referring specifically to the drawings, the numeral 5 designates the cabinet as a whole, formed of precast cement slabs, although it will be apparent that other cabinet structures may be employed. The cabinet comprises a bottom 6, top 7, sides 8 and 9 and back 10. The sides 8 and 9 and back 10 are provided with dowels 11, adapted, at assembly, to engage preformed dowel openings 12 in the top and bottom sections 6 and 7. As shown, the cabinet has no front wall and will be covered and uncovered by a closure door 13, indicated as a whole and to be later described in detail. The top and bottom sections 6 and 7, adjacent their left front corner, have cast therein, bushings 14 and 15, for the rotatable reception of hinge pins, to be described. In assembling the cabinet, the abutting edges of the several sections are provided with a fluent coating of cement or mortar and the side and back sections 8, 9 and 10 placed upon the base 6, with the dowels engaging in the openings 12. The top section is then placed in position upon the side and back sections, with the dowels engaging in the openings 12 therof. The joints are troweled to provide a finished appearance. If found desirable, a suitable hook device 16 may be first engaged over a rear dowel before the top is placed in position, upon which any suitable form of deodorant device may be suspended. It will be apparent, since the closure door must first engage the bushings 14 and 15, that the top will not be placed in position until the door is placed. Since it is desirable, that the door shall fully underlie the top front edge, one side wall 8 is formed slightly shorter in order that the door will squarely close to underlying position and be parallel with the front edges of the cabinet.

The door 13 comprises a generally rectangular sheet of metal of proper gauge, 17, the circumferential edges of which are preferably bent upon themselves for reinforcement and finish. The left or hinge side of the door is bent at a right angle to form an inwardly extending flange 18.

The door is rigidly reinforced adjacent its vertical edges, by angle irons 19 and 20, welded or bolted to the panel of the door. Extending between the angles 19 and 20 and likewise welded or bolted to the door panel and to the angles 19 and 20, are horizontal angle irons 21 and 22. The angle irons 21 and 22 are spaced upward and below the upper and lower marginal edges of the door, as clearly shown. Welded to the upper and lower terminal ends of the angle iron 20 and flush with the ends thereof, are blocks 23, carrying vertically and axially arranged hinge pins 24. The hinge pins 24 are engaged to rotate within the bushings 14 and 15 and are assembled to such position when the top section 7 is placed in position.

Projecting outwardly from the door at an angle with respect thereto and in horizontal alignment with the angle iron 21, is an angle iron 25. The angle iron 25 is welded at its inner end to the angle iron 20 and lower hinge block 23 and projects outwardly from the door at an angle of approximately 45 degrees. Welded to the outer end of the angle iron 25 and extending at right angle thereto and equidistantly upon either side, is an angle iron 26. As shown, the angle irons 25 and 26 have one flat surface uppermost. Secured to the upper flat surfaces of the angle irons 25 and 26, as by welding, is a circular metallic band 27, forming, with the angles irons 25 and 26, a circular socket for the reception of the conventional circular bottom of trash or garbage cans or other containers, see particularly Figure 2. An additional combined brace bar and can guide 28 is welded to the band 27 and projects upwardly and inwardly at an angle, with its terminal end welded to the inner side of the angle iron 20, adjacent its top. The bar not only serves to give additional strength to the supporting structure of the band 27 and angles 25 and 26, but is a means for directing the storage can to its seat within the socket.

As clearly shown, the cabinet front is inclined toward the rear and, in use, the door 13 is hinged at an angle to the perpendicular, thus, a can or other article upon the support socket will obviously, due to the overbalancing of the door, cause the door to swing to its closed position against the front edge of the side wall 8. Swinging the door beyond the position of a right angle with respect to the cabinet, will cause the door to remain open, since the center of gravity has passed the axial position of hinge pins 24. In all other positions, the door will automatically close, regardless of whether or not a storage receptacle is supported thereon. The rigidity of the angle irons 19, 20, 21, 22, 25 and 26 presents a structure that will maintain its shape and relative position against warping or twisting under load. While the bar 28 is a decided advantage, it is not essential to the support of the socket, since actual tests of loads upon the socket have been made up to 250 pounds, without in any way affecting the door structure or its free operation.

It will therefore be seen from the foregoing, that a very ornamental and highly desirable form of storage cabinet has been provided. All metal parts are treated against rusting and obviously, there will be no decay or possibility of disarrangement of parts, since the device, after assembly, is a unitary structure and the door cannot be removed, except by first removing the top section 7. The cabinet is substantially waterproof and is easily cleaned by flushing with the ordinary garden hose. While the cabinet was primarily

designed for use as a storage cabinet for garbage cans or the like, it follows, that it has many other uses, such as grain storage, flour storage and many other uses where it is desired that the closure door carries the storage receptacle and will automatically close upon release.

It is to be understood, that the invention is not limited to the precise arrangement shown, but that it includes within its purview whatever changes fairly come within either the terms or the spirit of the appended claims.

Having described my invention, what I claim as new and desire to secure by Letters Patent is:

1. A storage device comprising a cabinet formed of precast concrete sections united by dowls and having its front side formed open and inclined rearwardly, said cabinet having a bottom, an inclined top and side and rear walls, bushings formed in the bottom and top at one side adjacent the front of the cabinet with the top bushing arranged rearwardly of the bottom bushing, a sheet metal closure door for the cabinet that is normally parallel with the inclined front of the cabinet, parallel angle irons secured to the inner surface of the door adjacent its side edges, horizontally arranged angle irons secured to the inner surface of the door and welded to the first named angle irons, hinge blocks welded to one side angle iron adjacent the top and bottom of the door, axially aligned and outwardly extending hinge pins carried by the blocks, said pins having rotatable mounting in the said bushings, an angle iron bracket arm welded to the last named angle iron and angularly positioned from the door in a plane at a right angle to the axis of the pins, said bracket arm extending from the axial center line of the hinge pins, a receptacle positioning band carried by the outer end of the bracket arm, a brace bar connected with the band and with the door, said door mounted to swing at an angle from the vertical corresponding to the angle of inclination of the cabinet front, whereby said door automatically closes upon release.

2. A sanitary storage device comprising a cabinet formed of precast concrete sections united at their edges to form a housing entirely open at its front side, said cabinet having a bottom and an inclined top and side and rear walls, the front side of the cabinet being inclined rearwardly, a sheet metal door for covering and uncovering the open side, vertically arranged angle irons welded to the inner surface of the door adjacent its outer side edges, transversely extending angle irons welded to the door and to the first named angle irons, hinge blocks welded to one of the side angle irons adjacent its top and bottom, hinge pins formed on the blocks and extending outwardly above and below the door and in axial alignment, bushings formed in the top and bottom of the cabinet adjacent its front side and to one side for the rotatable reception of the hinge pins the positioning of the hinge pins in the bushings causing the door to be angularly disposed from the vertical, the hinging of the door being parallel with the side walls of the cabinet, an angle iron welded to one vertical angle iron of the door and projecting inwardly from the door at an angle and at a right angle from the axis of the hinges, a cross head angle welded to the terminal end of the last named projecting angle, an upstanding metallic band secured to the cross head for positioning a removable receptacle upon the cross head in spaced relation to the inner surface of the door, a combined brace and receptacle guide

secured to the band and to the door adjacent its upper hinge block.
